(57) **CLAIM**

The ornamental design for a spice grinder, substantially as shown and described.

DESCRIPTION

FIG. 1 is a front elevational view of a first configuration of the spice grinder assembly;

FIG. 2 is a rear elevational view of the spice grinder assembly of FIG. 1;

FIG. 3 is a left side elevational view of the spice grinder assembly of FIG. 1, wherein the right side elevational view is a mirror image thereof;

FIG. 4 is a top plan view of the spice grinder assembly of FIG. 1;

FIG. 5 is a bottom plan view of the spice grinder assembly of FIG. 1;

FIG. 6 is a front elevational view of a second configuration of the spice grinder assembly;

FIG. 7 is a rear elevational view of the spice grinder assembly of FIG. 6;

FIG. 8 is a left side elevational view of the spice grinder assembly of FIG. 6.

FIG. 9 is a top plan view of the spice grinder assembly of FIG. 6; and,

FIG. 10 is a bottom plan view of the spice grinder assembly of FIG. 6.

The broken lines are for illustrative purposes only and form no part of the claimed design.
